His Attorney.

UNITED STATES PATENT OFFICE.

ROBERT E. NEWELL, OF IRWIN, PENNSYLVANIA.

SAFETY VALVE.

Application filed September 20, 1919. Serial No. 325,206.

To all whom it may concern:

Be it known that I, ROBERT E. NEWELL, a citizen of the United States, and a resident of Irwin, in the county of Westmoreland and 5 State of Pennsylvania, have made a new and useful Invention in Safety Valves, of which the following is a specification.

My invention relates to safety valves for gas burners and consists of a device which 10 automatically closes the burner supply valve whenever the burner flame is extinguished as by wind, atmospheric concussion, interruption in pressure or other cause.

My device utilizes a thermostatic member 15 for controlling the supply valve and one of the objects of my invention is to space the thermostatic member from the burner flame so that the metal in the thermostat will not be subjected to continuous exposure to the 20 burner flame yet will be controlled thereby. Another object is to concentrate some of the burner heat on the thermostat when the gas is ignited so as to make the thermostat quickly responsive to the ignition. Another 25 object is to enable the spacing of the valve and burner from each other without affecting the efficiency of the automatic features of the device.

Briefly, the device comprises a valve in 30 which the plug is normally held in closed position by a spring. A band surrounds a portion of the plug and is adapted to grip the latter to hold it in any desired position. A flat spring tends to hold this band in gripping 35 position but is prevented from functioning by a thermostatic member except when the latter is heated. Manual turning of the plug to open position accompanied by application of heat to the thermostatic member results in an automatic gripping of the plug in open position. Subsequent cessation of the heat causes the thermostat to release the gripping means, whereupon the plug returns to its closed position.

The detailed description of my device is 40 illustrated in the accompanying drawings in which Figure 1 is a vertical section and view of the valve with portions of the stove to which it is applied and the burner controlled by it; Fig. 2 is a front view and partial section of the same; Fig. 3 is a section on line 3-3 of Fig. 1 and Fig. 4 is a section on line 4-4 of Fig. 1.

I have shown the device as applied to the

side 1 of a gas heater and controlling the 55 burner 2. Those parts which project outside of the stove are enclosed by a casing 3. The gas connection is to the stem 4 which leads to burner 2 thru a valve 5 provided with a plug 6. Plug 6 is operated by a 60 handle 7 and has an integral drum 8. Drum 8 is encircled by a band 9 one end of which is attached to a fixed pin or lug 10 located on the valve body; the other end is attached to one arm of a bell crank 11. This bell 65 crank is pivoted to the valve body at 12 and its other arm bears against a flat spring 13 which is attached to the valve body at a point removed from its contact with the bell crank. The tendency of spring 13 is to 70 move bell crank 11 in a clockwise direction.

An extension 14 on the body aids in attaching the device to the heater and forms a spaced securing point for a thermostatic member 15 which is composed of a strip of 75 metal formed of two or more alternate layers of metals having different coefficients of expansion. The strip is turned so that the metal having the smallest coefficient of expansion is nearest spring 13. When member 15 is heated, it curves in an arc indicated by the dotted lines in Fig. 1.

A cable 16 connects spring 13 to member 15 and when the latter is cold and in its normal position it deflects spring 13 to the 85 left thru cable 16. By using a tension connection it is possible to locate the thermostatic member and the valve independently of each other. While I have shown these parts in my preferred construction as being 90 adjacent, it would be feasible to have the valve at a point remote from the burner and in some applications of my device such a location of the valve might be advantageous or necessary. I prefer cable 16 to be flexible 95 which will permit it to be led around intervening parts if desired. One end of the cable is threaded and fitted with nuts to permit adjustment.

When member 15 is heated it releases its 100 pull on spring 13 and frees the latter which actuates bell crank 11 so as to tighten band 9 about drum 8.

A shield 17, mounted on member 15, is 105 curved as best shown in Fig. 4, and when member 15 is cold it holds shield 17 so that the shield will extend over nipple 18 in burner 2. When member 15 is hot and de-

flected from its normal position, the end of shield 17 will be spaced from the nipple 18 as indicated by the dotted lines in Fig. 4.

5 A washer of asbestos or other non-conducting material is inserted between shield 17 and member 15.

10 A spiral spring 19 is attached at one end to drum 8 and at the other end to the valve body and being under initial tension tends to maintain the valve in the closed position shown in Fig. 2 with a lug 20 on the plug engaging a notch 21 on the body. 22 represents a hole in the heater casing to permit access to the burner.

15 *Operation.*—The gas is lit in the usual manner by turning handle 7 to aline the plug passage with the valve openings and applying a match to the burner nipple. The handle must be held in open position for a few seconds during which time the heat of the flame at nipple 18 is deflected by shield 17 to thermostatic member 15 which bends as indicated slackening the pull on cable 16 when spring 13 will move bell

20 25 crank 11 so as to tighten band 9 on drum 8 and hold the latter in position. When this movement is accomplished the manual hold on the handle may be released.

30 It will be noted that the above described movement brings shield 17 to a position where it no longer deflects the heat from nipple 18. The device is designed so that the heat radiated by the burner will be sufficient to maintain the thermostatic member in its deflected position, but to secure quick action, the first heating thereof is accelerated by means of the shield.

35 Because of the shield action, I can space the thermostatic member from the flame and avoid the damaging effect of the continued exposure of the metal to a higher temperature than that necessary to maintain its distortion. The non-conducting washer interrupts the transmission of heat thru the shield to the thermostat and further protects the latter.

40 45 50 When the flame is extinguished, the cooling thermostat 15 returns to its normal position releasing the grip of band 9 on drum 8. Spring 19 immediately returns the valve to the closed position thus stopping the flow of gas. When the burner is lit, the friction of band 9 on drum 8 will be sufficient to resist the action of spring 19 but will not be great enough to interfere with easy adjustment of the valve opening by any person desiring to regulate the burner. This is due to the fact that after initial movement of the thermostatic member, variations in its position do not affect the frictional grip of band 9 because of the character of the connection between member 15 and spring 13. The thermostat has no effect upon the holding device except when the former is very near the position shown in full lines in Fig. 1.

This feature has the further advantages of preventing binding of the parts involved or any undue strain on same which exists in those devices in which continued movement of a thermostatic member is accompanied by increased friction or pressure by the member it controls.

I claim:—

1. In combination with a fuel burner, a valve, a thermostat controlling said valve 75 and a shield adapted to concentrate the heat of said burner on said thermostat until the latter is heated and then to move with said thermostat to a position where said thermostat will be heated by radiation only. 80

2. In combination with a fuel burner, a thermostatic member spaced from the burner flame, a shield integral with said member and adapted to overspan the space between said member and said flame when said member is cool so as to deflect the heat from said flame to said member, but to reach short of said flame when said member is distorted by heat. 85

3. In an automatic safety valve for fuel burners, a valve plug, a band encircling said plug and thermostatically controlled means adapted to tighten said band upon said plug when the fuel supplied by said valve is burning. 90

4. In a safety valve for fuel burners, a valve plug, a drum operating therewith, a band encircling said drum and means adapted to frictionally engage or to disengage said band and said drum. 95

5. In a safety valve for fuel burners, a valve plug, a drum operating therewith, a band encircling said drum and thermostatically controlled means adapted to frictionally engage or to disengage said band and said drum. 100

6. An automatic safety device for fuel burners comprising a valve, a spring adapted to maintain said valve in closed position, a band about said valve, a thermostatic strip adapted to be heated by the burner supplied thru said valve, means for tightening said band about said valve and a connection between said means and said strip whereby said strip normally holds said means in an inoperative position but when heated permits said means to operate to prevent said spring from functioning as described. 105

7. In combination with a burner, a supply valve for controlling the delivery of fuel to said burner, means for yieldingly holding the valve closed, an element for frictionally engaging the valve and holding it in set open positions, a spring tending to hold said element in engagement with said valve, and a thermostatic element responsive to heat generated by the burner, and movable in response to decreasing temperature to oppose the force of said spring as transmitted to said element. 110

8. In combination with a burner, a supply valve for controlling the delivery of fuel to said burner, means for yieldingly holding the valve closed, an element for frictionally engaging the valve and holding it in set open positions, a spring tending to hold said element in engagement with said valve, and a thermostatic element responsive to heat generated by the burner, and movable in response to decreasing temperature to oppose the force of said spring as transmitted to said element. 115

8. In combination with a burner, a valve for controlling the delivery of fuel thereto, means for controlling the operation of said valve, a thermostatic element responsive to heat generated by the burner, for controlling the operation of said means, and a deflector movable with the element for decreasing the direct heat delivered to the element when the element moves in response to increasing heat.
9. In combination with a burner, a valve for controlling the delivery of fuel thereto, means for controlling the operation of the
- valve, a thermostatic element responsive to heat generated by the burner, and controlling the operation of said means, and a deflector for directing heat from the burner to said element and movable in response to increasing heat to reduce the amount of heat so directed.
- In testimony whereof, I have hereunto subscribed my hand this 19th day of September, 1919.

ROBERT E. NEWELL.
